INDICATING DEVICE

Jean E. Masbach, New York, N. Y.

Application June 29, 1934, Serial No. 732,989

7 Claims. (Cl. 35—59)

This invention relates to indicating devices and more particularly to means carried by a bottle or other container for finger nail polish or other cosmetics, to give an accurate indication of the 5 coloration of the nail or other part to which the contents of the container may be applied.

It is the principal object of my invention to provide a simple indicating means of the above character which will not materially increase the 10 manufacturing cost of the bottle or container and which will enable the prospective purchaser to obtain positive knowledge of the particular color shade which will be imparted to the nail by application thereto of the contents of the 15 container.

To this end the invention, in one of its embodiments, is characterized by the provision of a sheet of tinted or colored celluloid, or other transparent or translucent material, attached to the container; said sheet and the container wall having relatively displaced portions to provide a recess or pocket for the reception of the finger. Thus the finger nail, when viewed through the tinted 20 sheet, will appear to be colored in a shade accurately indicative of that which would result from actual application of the container contents to the nail.

As a subsidiary feature I may provide a label attached to the surface of the bottle or container and having parts thereof associated with the celluloid sheet to represent the uncolored tip and base portions of the finger nail.

A further object of the invention is to provide an indicating means for the above purpose, to 35 be either permanently or removably associated with a supporting body and which, in one embodiment thereof, may include a plurality of finger receiving pockets or recesses having differently or similarly colored transparent walls.

With the above and other objects in view, the invention consists in the improved indicating device and in the form, construction and relative arrangement of its several parts, as will hereinafter be more fully described, illustrated in the 40 accompanying drawing and subsequently incorporated in the subjoined claims.

In the drawing wherein I have disclosed several simple and practical embodiments of the invention, and in which similar reference characters designate corresponding parts throughout the several views;

Figure 1 is a side elevation of a cosmetic bottle or container provided with one embodiment 55 of my invention.

Fig. 2 is a similar view, the label and transparent member being removed.

Fig. 3 is a detail view of the label.

Fig. 4 is a sectional view taken on the line 4—4 of Fig. 1.

Fig. 5 is an elevation similar to Fig. 1 showing another arrangement of the device.

Fig. 6 is a perspective view illustrating a modified embodiment of the invention.

Fig. 7 is a sectional view taken on the line 7—7 of Fig. 6, the supporting body being omitted.

Fig. 8 is a detail sectional view showing another modified form of the device.

Referring in detail to the drawing, the bottle or container 5 may be of any desired size, shape and capacity and formed of glass or other materials. In the manufacture of the container it is provided with an external recess 6 in one wall thereof. In Fig. 1 of the drawing I have shown this recess in one side wall and extending obliquely upward from the lower right hand corner of the container. It may, however, be otherwise located, as for instance in the vertical center line of the bottle, as shown in Fig. 5.

At one of its ends the recess 6 opens upon the periphery of the container and the open side of the recess is surrounded by a channel or rabbet 7, though, if desired this feature may be omitted. The wall of the recess leading to this channel is preferably longitudinally and transversely curved. 20 A correspondingly curved, thin sheet of celluloid or other transparent or translucent material, indicated at 8 is arranged over and in opposed relation to the recess 6. The marginal edges of this transparent sheet are outwardly flanged and secured by means of a suitable adhesive in the channel or rabbet 7, as clearly shown in Fig. 4 of the drawing.

The celluloid sheet 8 is colored by any approved method to accurately indicate upon the nail of a finger positioned in the recess 6, the actual color which will be imparted to the nail by the application thereto of the contents of the particular container.

I may also provide means in association with the transparent sheet 6 for indicating the white tip and base portions of the nail to which the polish is not applied. Thus, the label 9, attached to the face of the container and which may bear suitable descriptive printing, is provided with an opening 10 through which the major portion of the transparent sheet 8 is exposed. At the opposite ends of this opening white or uncolored portions of the label, indicated at 11, are superimposed upon the sheet 8 and adhesively secured 55

thereto. However, any other equivalent means may be provided for this purpose.

Fig. 8 illustrates an alternative method of attaching the celluloid sheet to the container. Thus, the surface of the container may be provided with spaced ribs 12 connected by the concave surface 13. The celluloid sheet 8' is initially formed in concavo-convex shape and provided with the inwardly extending flanges 14 at its opposite side edges. To apply the sheet 8' it is necessary to first expand the side walls thereof outwardly. Upon release thereof the flanges 14 lock behind and securely grip the ribs 12 on the container. Other alternative means for attaching the celluloid sheet will readily suggest themselves from the above examples.

In Figs. 6 and 7 I illustrate an application of my invention which is primarily designed for counter use. As shown a dummy of wood or other material, indicated at 15, constitutes a supporting body for a shell 16. Vertically contiguous portions of this shell are struck outwardly to form a series of open-ended, finger receiving pockets 17. The entire shell may be of transparent material or only those portions forming the walls of the pockets 17 may be transparent and suitably colored. The colors of the respective portions may be different, as indicated in the drawing, or all of one color, as preferred. Thus the appearance of all the fingers of one hand may be simultaneously viewed through the pocket walls, and an accurate indication obtained of the color which will best meet the individual preference.

From the above description, considered in connection with the accompanying drawing the construction and several advantages of my invention will be readily understood. The device while of very simple construction is convenient and serviceable in practical use. By means thereof the observer can obtain an accurate indication of the color shade which will be imparted to the nails by means of the polish in the particular container with which the device is associated. Heretofore, even though the material may be vended in glass containers this was not possible. The apparent color of the polish therein was deceptive owing to the refraction of light through the glass walls of the container. My invention will therefore promote the sale of such cosmetic materials with greater satisfaction to the purchaser.

I have herein shown and described several embodiments of the invention, but it will be understood that, insofar as the essential features thereof are concerned, the same might also be incorporated in various other alternative structural forms. Accordingly I reserve the privilege of resorting to all such legitimate changes in the form, construction and relative arrangement of the several elements as may fairly be considered within the spirit and scope of the invention as claimed.

What I claim is:

1. A container for nail coloring material having an external finger receiving recess, open at one end and provided with a side wall of transparent material colored correspondingly to the contents of the container and through which the nail of a

finger positioned in said recess is viewed, to indicate the coloration of the nail by the application of the container contents thereto.

2. In combination with a container for nail coloring material, a transparent member colored correspondingly to the contents of the container and attached to said container, said member and container having opposing parts relatively shaped and spaced apart to form a finger receiving pocket open at one end, the finger nail adapted to be positioned adjacent to said transparent member, to be viewed therethrough and thereby indicate the coloration of the nail by the application of the contents of the container.

3. A container for nail coloring material having an external finger receiving recess, open at one end thereof, and a concavo-convex sheet of transparent material colored correspondingly to the contents of the container and attached to the container and extending over said recess, through which the finger nail is viewed, to indicate the coloration of the nail by the application of the container contents thereto.

4. A container for nail coloring material having an external finger receiving recess, open at one end and provided with a side wall of transparent material colored correspondingly to the contents of the container, and through which the nail of a finger positioned in said recess is viewed, to indicate the coloration of the nail by the application of the container contents thereto, and spaced uncolored parts superimposed upon said transparent material, indicative of the uncolored tip and base portions of the nail.

5. A container for nail coloring material having a finger receiving recess open at one end and provided with a side wall of transparent material colored correspondingly to the contents of the container and through which the nail of a finger positioned in said recess is viewed, to indicate the coloration of the nail by the application of the container contents thereto, and a label attached to the container and having parts thereof superimposed upon said transparent side wall, indicative of the uncolored tip and base portions of the nail.

6. In combination with a supporting body, a shell partially enclosing said body and having a plurality of contiguous portions formed to provide a series of finger receiving pockets, the walls of said pockets, through which the nails of fingers positioned therein are viewed, being transparent and colored, to indicate the coloration of the nails by the application of a cosmetic material thereto.

7. In combination with a rigid supporting body, a transparent member colored correspondingly to the color of coloring material when applied to the finger nail, said member comprising a longitudinally and transversely curved wall, and means for mounting said member upon said body, with opposite side edges and one end edge of said wall in contact with a surface of said body and the other end edge of the wall spaced from said surface, to thereby form an elongated finger receiving pocket, completely closed along opposite sides and one end thereof and open at its other end for the insertion of the finger into said pocket.

JEAN E. MASBACH.
